CLAIM

We claim the ornamental design for a water timer, as shown and described.

DESCRIPTION

FIG. 1 is a perspective view of a water timer;
FIG. 2 is a front elevational view of the water timer of FIG. 1;
FIG. 3 is a left side elevational view of the water timer of FIG.

1;
FIG. 4 is a right side elevational view of the water timer of FIG. 1;
FIG. 5 is a rear elevational view of the water timer of FIG. 1;
FIG. 6 is a top view of the water timer of FIG. 1; and,
FIG. 7 is a bottom view of the water timer of FIG. 1.
The broken lines in the foregoing drawings are for the purpose of illustration and form no part of the claimed design.
